(57) **CLAIM**

The ornamental design for a display screen or portion thereof with graphical user interface, as shown and described.

DESCRIPTION

The FIGURE is a front view of a display screen or portion thereof with graphical user interface showing my new design.

The dash-dash broken lines shown in the FIGURE are for illustrative purposes only and form no part of the claimed design. The dash-dot broken lines shown in the FIGURE depict a portion of the display screen and form no part of the claimed design.
